UNITED STATES PATENT OFFICE.

PHILIP H. KLEIN, JR., OF NEW YORK, N. Y., ASSIGNOR TO THE BERGMANN ELECTRIC AND GAS FIXTURE COMPANY, OF SAME PLACE.

HOLDER FOR INCANDESCENT ELECTRIC LAMPS.

SPECIFICATION forming part of Letters Patent No. 426,189, dated April 22, 1890.

Application filed September 5, 1889. Serial No. 323,071. (No model.)

To all whom it may concern:

Be it known that I, PHILIP H. KLEIN, Jr., a citizen of the United States, residing at New York, in the county and State of New York, 5 have invented a certain new and useful Improvement in Holders for Electric-Light Burners, of which the following is a specification.

This invention is designed particularly for 10 connecting an incandescent lamp with a gas-fixture; and it consists in a metal arm having one end provided with a clamping-ring and the opposite end with a threaded portion to engage an electric lamp.

15 In the accompanying drawings, Figure 1 is a side view of the holder attached to a gas-burner. Fig. 2 is a top view of the holder, and Fig. 3 represents a portion of the blank from which the threaded end is formed.

20 Referring by letter to the drawings, A designates the holder consisting of a flat strip of metal having a twist *a* in its main portion, so that the width of the metal strip at one end of the twist is in a horizontal plane and at 25 the other end in a vertical plane. The portion having its greatest width in a vertical plane is turned to form a collar or ring *B* to

engage over a gas-burner, and a clamping-screw *b* serves to clamp the collar around the burner.

30 Ordinarily it has been necessary to remove the burner and place the collar of a holder below it in the manner that globe-supports are placed. In the present invention the collar fits over the burner, so, of course, it is not 35 necessary to remove it.

Referring to Fig. 3, it will be observed that one end of the strip has lateral projections *c*, which, when turned or curved so that their edges meet, form the tubular head *C*, which 40 may be threaded on its outer side to engage an incandescent burner, and the opening *c'* allows for the passage of the wires.

Having described my invention, what I 45 claim is—

A holder for electric lights, consisting of a flat metal strip having a twisted portion, a threaded tubular portion, and a collar portion having a clamping-screw, substantially as specified.

PHILIP H. KLEIN, JR.
